UNITED STATES PATENT OFFICE.

BENJAMIN F. OLER, OF ELMHURST, NEW YORK, ASSIGNOR TO THE UNION SWITCH AND SIGNAL COMPANY, OF SWISSVALE, PENNSYLVANIA, A CORPORATION OF PENNSYLVANIA.

CONTROLLING APPARATUS FOR RAILWAY CARS OR TRAINS.

1,070,283.

Specification of Letters Patent. Patented Aug. 12, 1913.

Application filed November 16, 1912. Serial No. 731,650.

To all whom it may concern:

Be it known that I, BENJAMIN F. OLER, a citizen of the United States, residing at Elmhurst, in the county of Queens and State 5 of New York, have invented certain new and useful Improvements in Controlling Apparatus for Railway Cars or Trains, of which the following is a specification.

My invention relates to means for the control 10 of automatic stopping devices for railway cars or trains.

I will describe one form of apparatus and circuits embodying my invention and then point out the novel features thereof in 15 claims.

In the accompanying drawings, Figure 1 is a diagrammatic view showing a portion of a railway having applied thereto one form 20 of apparatus and circuits embodying my invention. Fig. 2 is a view showing in side elevation a portion of a car and one form of apparatus carried thereby, and showing also one form of apparatus along the trackway. Fig. 3 is an end view of Fig. 2, looking at 25 the right hand end of Fig. 2. Fig. 4 is a view showing in detail a slow acting circuit controlling device shown diagrammatically in Fig. 1.

Similar reference characters refer to similar parts in each of the several views.

Referring first to Fig. 1, I have here shown a stretch of railway track divided into block sections *a*, *b*, *c*, *d*, etc. Traffic along the railway is governed by railway 35 signals *S*, *S'*, *S²*, *S³* etc. located adjacent the entrance ends of the block sections. These signals are controlled by track circuits each comprising a source of current 19 and a track relay *R*, *R'*, *R²*, *R³* etc. The control of 40 the signals by these track relays forms no part of my invention, hence for the sake of clearness I have omitted the control circuits from the drawing. For each signal I provide a trip 10 located in or adjacent to the 45 trackway. Each trip is preferably located in the rear of its signal a distance at least equal to the maximum braking distance of cars or trains, so that if the brakes of a car or train are applied by a trip 10, the car or 50 train will be brought to a stop before reaching the next signal. As here shown, (see also Figs. 2 and 3) each trip is constantly

in tripping position, although I do not wish to be limited to this particular arrangement, or to the particular form of trip shown. Extending along the trackway for a short distance in the rear of each trip are two ramp rails 13 and 18, from which current is taken into a car or train by suitable contacts for a purpose hereinafter explained. Located intermediate the ends of each block section is another trip 10^a, in the rear of which extend ramp rails 13^a and 18^a.

Referring now to Figs. 2 and 3, which views are partly diagrammatic in so far as they illustrate a car or vehicle traveling along a trackway and the relative arrangement of certain parts carried thereby, 11 designates a device carried by the car or vehicle and arranged thereon so that it may at times engage a trip 10 to affect apparatus on the car having to do with controlling the car. As here shown, the apparatus having to do with controlling the car is a valve 12, and the device 11 is an arm operatively connected with the valve 12. This valve is adapted to close and open a pipe 36 connected with the train pipe 35. When the valve 12 is moved by reason of the arm 11 engaging a trip 10, the pipe 36 is opened to the atmosphere and an automatic application of the air brake is the result. This is well understood in the art.

The arm 11 and the valve 12 are suitably supported so that the arm 11 may be moved into and out of position for engagement with a trip 10, for which movement I provide a suitable actuating mechanism on the car. The operation of this actuating mechanism is controlled in a manner which I will now explain. As here shown the arm 11 and valve 12 are suitably supported by a bar 34^a which is pivoted on the car. The full line position in Fig. 2 indicates the operative position of the arm 11, that is, the position in which this arm will engage the trip 10, and the dash line position indicates the inoperative position of this arm. The mechanism for moving the arm 11 from its operative to its inoperative position may be any desired. As here shown this actuating mechanism comprises a cylinder 27, in which moves a piston 28, to which piston is connected a piston rod 28^a and which piston

rod is connected with a crank 33 pivoted at 31. One end of the crank 33 is connected by a link 34 with the bar 34^a, while the other end of the crank 33 is connected with 5 a rod 32 which rod is constrained by suitable guides to move longitudinally. This rod 32 is surrounded by a coiled spring 32^a. One function of the spring 32^a is to assist gravity in returning the arm 11 to its operative position. The pivotal point 31 and the connecting points of the link 34 are preferably arranged in a straight line when the arm 11 is in its operative position, so that the crank 33 and the link 34 form a lock to hold the 10 arm 11 against accidental movement out of its operative position by exterior means.

The piston 28 is moved in the cylinder 27 by air pressure from a pipe 24 which pipe is supplied with air from any suitable source. 20 The supply of air pressure from the pipe 24 to the cylinder 27 is controlled by means of a valve 21, the operation of which valve is in turn controlled by an electromagnet 15. Current is at times supplied to this magnet 25 from outside the car by means of two shoes 14 and 20 which may engage the ramp rails 13 and 18 respectively. These shoes are connected respectively with the terminals of the magnet 15 by wires 16 and 17. The magnet 30 15 is of course usually deenergized, so that valve 21 is in position to close pipe 24 and open the cylinder 27 to atmosphere through port 37. Hence the arm 11 is usually in position for engagement with trip 10.

35 It will be seen from the foregoing that as a car or train proceeds along the railway in the direction indicated by the arrow in Fig. 1, when the contact shoes 14 and 20 engage a pair of ramp rails 13 and 18, or 13^a and 18^a, 40 if these ramp rails are connected with a source of current, the electro-magnet 15 on the car is energized thereby reversing the position of valve 21, which latter then disconnects the cylinder 27 from atmosphere 45 and connects it with the air pipe 24 so that the arm 11 is moved out of its operative position before it reaches trip 10, hence the valve 12 will not be open and the brakes will not be applied. If, however, the circuit for 50 the ramp rails is open at any point, so that these rails are not connected with a source of current, the electro-magnet 15 will not be energized, so that the arm 11 will remain in operative position and will be engaged by the trip 10; the valve 12 will then be opened and the brakes will be applied so that the car 55 or train will be brought to a stop.

Each pair of ramp rails 13 and 18 is provided with two circuits, a "normal" circuit 60 and an "auxiliary" circuit, which circuits are controlled by one or more of the track relays. For example, referring to Fig. 1, the normal circuit for the ramp rails 13 and 18 in the rear of signal S' is from battery B through wires 40 and 41, contact 42 of relay

R², wire 43, contact 44 of relay R', wires 22 and 45, ramp rail 18, thence through the shoes, wires and magnet on a car when a car is over the ramp rails, ramp rail 13, wire 46, and common wire 0 to battery B. The normal circuit for the pair of ramp rails adjacent each signal is similar to that just traced. The auxiliary circuit for each pair of ramp rails 13 and 18 will be traced hereinafter. Each pair of ramp rails 13^a and 18^a is similarly provided with a normal circuit and an auxiliary circuit. For example, the normal circuit for ramp rails 13^a and 18^a of block section b is from battery B through wires 40 and 41, contact 42 of relay R², wires 43 and 23, ramp rails 18^a and 13^a and the conductors and apparatus on a car or train over these ramp rails, wires 25 and 0 to battery B. The normal circuit for each pair of ramp rails 13^a and 18^a is similar to that just 85 traced. The auxiliary circuit for these ramp rails will be traced hereinafter.

The auxiliary circuit for each pair of ramp rails is controlled by a slow acting circuit controller T, T', etc., each of which may 90 be of a type such as I will now explain, referring to Fig. 4. 57 is a solenoid which operates a plunger 58. The lower end of the plunger is pinned to an arm 60 which arm is mounted to rotate freely on a shaft 95 59. The outer end of the arm 60 is provided with a counterweight 64 which latter, together with the weight of the plunger and arm, insures that when the solenoid is deenergized the parts will occupy their lowest 100 position against a stop 66.

38 is a contact plate which rests normally on a seat 67 which latter is suitably supported in a manner not shown. When the plunger 58 is raised by the solenoid, the 105 counterweight 64 engages the plate 38 and raises it into engagement with the contact fingers which are indicated diagrammatically. When the plunger 58 again drops, the plate of course falls away from the fingers by gravity. The upward movement of the plunger and arm is retarded by a means which I will now explain. Fixed on the shaft 59 is a ratchet wheel 62 whose teeth are engaged by a pawl 61 pivoted to the arm 60. 110 This pawl and ratchet are so arranged that when the arm 60 is being raised the ratchet wheel 62 is rotated, but that when the arm 60 is falling, the pawl 61 slides freely over the teeth of the ratchet wheel and the latter 115 is not rotated. The shaft 59 is constantly connected by means of gearing with a fan 63, the gearing being so arranged that the fan rotates at a speed many times greater than the speed of shaft 59. By means of 120 this gearing and fan, the shaft 59 is constrained to rotate slowly.

The operation of the circuit controller is as follows:—The parts of the controller normally occupy the positions in which they 125

are shown in Fig. 4. When now the solenoid 57 is energized it draws the plunger 58 upwardly, but this upward movement is retarded by the gearing and fan 63, so that a considerable period of time is required for the parts to move to such position that the contact 38 is closed. When, with the parts in the raised position, the solenoid becomes deenergized, the plunger 58 and arm 60 will 10 return quickly to their lower position against the stop 66 because then the pawl 61 slides over the ratchet wheel 62 and the gearing remains stationary.

Referring again to Fig. 1, the auxiliary circuit for the ramp rails 13 and 18 just in the rear of signal S^2 is from battery B through wire 39, contact 38 of circuit controller T^2 , wires 47 and 45, ramp rails 18 and 13, wire 46, common wire 0 to battery B. This circuit is normally open at contact 38. The solenoid 57 of circuit controller T^2 is provided with the following energizing circuit—from battery B', through wires 40 and 48, back contact 49 of relay R' , wire 50, contact 51 of relay R^2 , wire 52, solenoid 57, wires 53 and 46, common wire 0 to battery B'. It will be seen that this energizing circuit is normally open at relay R' , but is closed when this relay opens as a car or train 25 enters block section b provided block section c is unoccupied. The period of time required for the complete operation of the circuit controller will be referred to hereinafter. Each pair of ramp rails 13 and 18 30 is provided with a similar auxiliary circuit, and the solenoid 57 of each circuit controller T , T' and T^2 is provided with a similar energizing circuit.

The ramp rails 13^a and 18^a of block section c are provided with the following auxiliary circuit—from battery B through wires 40 and 48, contact 49 of relay R^2 , wires 50, 54 and 55, contact 38 of circuit controller T^6 , wires 56 and 23, ramp rails 18^a and 13^a, wires 25 and 0 to battery B. This circuit is normally open at contact 38. The solenoid 57 of circuit controller T^6 is provided with the following energizing circuit—from battery B through wires 40 and 48, contact 49 of relay R^2 , wires 50 and 54, solenoid 57, wires 68, 25 and 0 to battery B. It will be seen that this energizing circuit for controller T^6 is normally open at relay R^2 , but is closed when this relay opens as a 55 car or train enters block section c . The period of time required for a complete operation of controller T^6 to close its contact will be referred to hereinafter. Each pair of ramp rails 13^a and 18^a is provided with a similar auxiliary circuit, and the solenoid 57 of each circuit controller T^4 and T^5 is 60 provided with a similar energizing circuit.

In the form of signaling shown in Fig. 1, each of the signals S , S' etc., is adapted to 65 give four indications, namely, "proceed",

"proceed, prepare to pass next signal at medium speed", "proceed, prepare to stop at next signal" and "stop". In the drawing, block section a is occupied by a car or train W, consequently signal S^3 indicates "stop," signal S^2 indicates "proceed, prepare to stop at next signal", signal S' indicates "proceed, prepare to pass next signal at medium speed", and signal S indicates "proceed". Since relay R^3 is open, the normal circuit for the pairs of ramp rails 13 and 18 just in the rear of signals S^3 and S^2 are open, as also the normal circuit for the pair 13^a, 18^a in block section c . The normal circuits however for the pairs of ramp rails 13, 18 in the rear of signals S and S' and for rails 13^a, 18^a in block sections a and b are closed, hence a following car or train W' may proceed through block section a at full speed. As this following car or train enters block section b , the opening of track relay R' sets circuit controller T^2 into operation. The time required for the contact 38 of this circuit controller to become closed is such that if the following 70 car or train W' slows down in block section b in order to pass signal S^2 at medium speed, the contact 38 will have closed before the car or train W' reaches the pair of ramp rails 13 and 18 adjacent the exit end of the block section b , and, the auxiliary circuit for these ramp rails being then closed, the car or train may pass the trip 10 at this point without the brakes being applied. If however, the car or train W' passes through 75 block section b at high speed, the time consumed in this block is less than the time required for the contact of circuit controller T^2 to close, so that when the car or train reaches the ramp rails 13 and 18 at the exit end of this block they are not energized and the train is therefore stopped by trip 10 at this point. Assuming that the car or train W' consumes the required amount of time in block section b , then as it enters 80 block section c , the opening of relay R^2 closes the energizing circuit for circuit controller T^6 , the operation of which then begins. The time required for the contact 38 of this controller to close is preferably about 85 the same as that required for controllers T' and T^2 , hence it will be seen that the following car or train W' must proceed through block section c at very low speed otherwise it will be stopped by trip 10^a in the middle 90 of this section. The auxiliary circuit for ramp rails 13 and 18 at the exit end of block section c cannot be closed because the circuit for circuit controller T^2 is open at contact 51 of relay R^3 , hence the car or train W' will 95 be brought to a stop by trip 10 adjacent the exit end of block section c if it attempts to pass this point.

Although I have herein shown and described only one form of apparatus and cir- 100

cuits embodying my invention, it is understood that various changes and modifications may be made therein within the scope of the appended claims without departing from the 5 spirit and scope of my invention.

Having thus described my invention, what I claim is:—

1. In combination, a railway, a plurality of successive block sections, track circuits 10 for the block sections, a trip adjacent the exit end of each block section, a contact rail extending in the rear of each trip, a device carried by a car and adapted to coact with the trips to control the car, means on the 15 car for rendering said device inoperative, a contact shoe on the car connected with the said means and adapted to engage with the contact rail, a normal circuit for each contact rail which circuit is controlled by the 20 track circuit for the next block section in advance, an auxiliary circuit for each contact rail, a slow acting circuit controller for the control of each auxiliary circuit, and a circuit for each of said circuit controllers 25 which circuit is controlled by the track circuit for the corresponding block section.

2. In combination, a railway, a plurality of successive block sections, track circuits for the block sections, a trip adjacent the exit 30 end of each block section, a contact rail extending in the rear of each trip, a device carried by a car and adapted to coact with the trips to control the car, means on the car for moving the device out of coacting 35 position, a contact shoe on the car connected with the said means and adapted to engage with the contact rail, a normal circuit for each contact rail which circuit is controlled by the track circuit for the next block section 40 in advance, an auxiliary circuit for each contact rail, a slow acting circuit controller for the control of each auxiliary circuit, and an energizing circuit for each circuit controller which circuit is controlled by the 45 track circuit for the corresponding block section.

3. In combination, a railway, a plurality of successive trips located adjacent the trackway, means carried by a car and adapted to coact with the trips to control the car, a contact rail extending in the rear of each trip for the control of the said means on the car, a normal circuit for each contact rail, means controlled by a car on the railway for 50 opening the circuits of one or more contact rails in the rear, an auxiliary circuit for each contact rail; a slow-acting device for closing each auxiliary circuit, and means controlled by a following car or train for setting into 55 operation the slow-acting device for the circuit of one or more of the contact rails next in advance of said following car.

4. In combination, a railway, a plurality of successive trips located adjacent the

trackway, means carried by a car and adapted to coact with the trips to control the car, a contact rail extending in the rear of each trip for the control of said means on the car, a normal circuit for each contact rail, means controlled by a car on the railway for 65 holding open the normal circuit of a contact rail in the rear thereof, an auxiliary circuit for each contact rail, a slow acting device for closing each auxiliary circuit, and means controlled by a car at a point on the 70 railway for setting into operation the said slow-acting device for the next succeeding contact rail.

5. In combination, a railway, a trip located adjacent the trackway thereof, a device carried by a car and adapted to coact with the trip to control the car, electrical means on the car for rendering said device inoperative to coact with the trip, a contact rail extending in the rear of the trip, a shoe 35 on the car connected with the said electrical means and adapted to engage the contact rail, a normal circuit for the contact rail, means controlled by a car on the railway in advance of the trip for holding the said 40 normal circuit open, an auxiliary circuit for the contact rail, a slow-acting circuit controller for the control of said auxiliary circuit, and means controlled by a car at a point in the rear of the trip for setting said 45 slow-acting circuit controller into operation.

6. In combination, a railway, a trip located adjacent the trackway thereof, a device carried by a car and adapted to coact with the trip to control the car, apparatus on the 100 car for rendering said device ineffective to coact with the trip to control the car, means on the trackway for controlling said apparatus, a normal circuit for said means, means controlled by a car or train on the railway 105 in advance of the trip for holding said normal circuit open, an auxiliary circuit for said first named means, time-controlled means for controlling said auxiliary circuit, and means controlled by a car or train at a 110 point in the rear of the trip for setting said time-controlled means into operation.

7. In combination, a railway track, a plurality of successive block sections, a trip located in the trackway adjacent the exit end 115 of each block section, a contact rail extending in the rear of each trip, a device on a car adapted to coact with the trips to control the car, means on the car for rendering said device inoperative to coact with the 120 trips to control the car, a contact on the car connected with the said means and adapted to engage the contact rail, a normal circuit for each contact rail, means controlled by a car or train in the next block section in advance for holding said normal circuit open, an auxiliary circuit for each contact rail, a slow acting circuit controller for the control 125

of each auxiliary circuit, and means controlled by a car or train entering a block section for setting into operation the circuit controller for the contact rail adjacent the 5 exit end of that section.

8. In combination, a railway track, a plurality of successive block sections, a trip located in the trackway adjacent the exit end of each block section, and a trip located in 10 the trackway adjacent the middle of each block section, a device carried on a car and adapted to coact with the trips to control the car, apparatus on the car for rendering the said device inoperative to co- 15 act with the trips to control the car, means in the trackway in the rear of each trip for controlling the apparatus on the car, a normal circuit for each of said means, said circuit for the means adjacent the exit end of 20 each block section being controlled by the presence of a car or train in each of the two block sections in advance and the circuit for the said means adjacent the middle of each block section being controlled by the presence 25 of a car or train in the block section in advance, an auxiliary circuit for each of said means, a slow acting circuit controller for each auxiliary circuit, and an energizing circuit for each circuit controller, which cir-

cuit is controlled by a car or train entering the corresponding block section. 30

9. In combination, a railway track, a plurality of successive block sections, a trip located in the trackway adjacent the exit end of each block section, and a trip located in 35 the trackway adjacent the middle of each block section, a device carried on a car and adapted to coact with the trips to control the car, apparatus on the car for rendering the said device inoperative to coact with the 40 trips to control the car, means in the trackway in the rear of each trip for controlling the apparatus on the car, a normal circuit for each of said means, which circuit is controlled by the presence and absence of a car 45 or train in the next succeeding block section, an auxiliary circuit for each of said means, a slow acting circuit controller for each auxiliary circuit, and an energizing circuit for each circuit controller, which circuit is 50 controlled by a car or train entering the corresponding block section.

In testimony whereof I affix my signature in presence of two witnesses.

BENJAMIN F. OLER.
